DOWEL BAR SUPPORT

Joe G. Curry, Indianapolis, Ind., assignor, by
mesne assignments, to Reconstruction Finance
Corporation, Boston, Mass., a corporation of
the United States

Application March 14, 1940, Serial No. 323,882

4 Claims. (Cl. 94—8)

The present invention relates to reinforcing devices for use in the building of concrete roads and the like and embodies, more particularly, an improved mechanism by means of which the adjacent ends of two sections of concrete and like material may be connected in such fashion that a desired relationship may be maintained therebetween under all conditions of service and regardless of the spacing between the abutting ends of the concrete sections.

In the construction of concrete roads, it is common practice to pour the concrete in sections, between the adjacent ends of which a suitable material is introduced to permit of relative movement between the sections due to expansion and contraction thereof by reason of temperature changes. The condition of the road remains more satisfactory by this sectional formation and considerable attention has been directed to the connecting structure by means of which the adjacent sections may be integrated.

The importance of maintaining the surface of the adjacent sections in the same plane will be readily apparent and, to this end, dowel bars have been inserted in the end structure of the concrete sections in order that the end sections may be reinforced and maintained in the same plane.

It has been extremely difficult to maintain these dowel bars effectively in a horizontal position during the pouring and setting of the cement and, to facilitate the proper positioning of these dowel bars, various structures have heretofore been provided with this end in view. However, in these various structures, the supporting mechanism for the dowel bars has served as a non-yielding tie mechanism which tends to make the connection rigid.

An object of the present invention is to provide a dowel bar support by means of which the dowel bar may be effectively supported in a position such that its axis lies parallel to the axis of the sections of the roadway, and maintained in such position during the pouring and setting of the cement, the structure being such as to avoid objectionable interconnection between the adjacent road sections after the concrete has set.

A further object of the invention is to provide a dowel bar support of the above character wherein the support structure is such as to permit of relative movement between the adjacent sections of concrete after the joint has set.

The foregoing objects are attained by providing a support structure having one part that is

adapted to be imbedded in the end of one of the concrete slabs and another part that is adapted to be imbedded in the adjacent end of the other slab, these parts being formed to support the dowel bar in a desired position and being connected in such fashion that relative movement therebetween is accommodated to provide for expansion and contraction of the concrete slabs and without tying the slab sections together.

10 Further objects of the invention will be apparent as it is described in greater detail in connection with the accompanying drawing, wherein:

15 Fig. 1 is a view in vertical section, taken through a dowel bar support constructed in accordance with the present invention and showing the manner in which a dowel bar is supported in position in proper relation to the adjacent concrete slab sections.

20 Fig. 2 is a perspective view of the support shown in Fig. 1, the view being taken from below and to one side of the support.

25 Fig. 3 is a view in section taken on line 3—3 of Fig. 1 and looking in the direction of the arrows.

Fig. 4 is a fragmental plan view showing the road surface with the support and dowel bars in the position which they assume during and after pouring and setting of the cement.

30 Fig. 5 is a plan view showing a modified form of the invention.

Fig. 6 is a view in section taken on the line 6—6 of Fig. 5 and looking in the direction of the arrows.

35 Fig. 7 is a perspective view taken from the top and at one end of the dowel bar support shown in Figs. 5 and 6.

Fig. 8 is a view in side elevation showing a further modification of the invention.

Referring to the above drawing, the adjacent ends of two concrete slabs of a road are shown at 10 and 11, being spaced to receive an expansion joint 12 by means of which relative movement of the slabs in response to changes in temperature may be accommodated. In order that the top surfaces of the adjacent ends of slabs 10 and 11 may be maintained in the same plane, a plurality of dowel bars 13 are provided, the dowel bars being so positioned that their axes lie parallel to the axis of the concrete slabs, thus preserving the top surfaces of the adjacent slabs 10 and 11 in the same plane regardless of the extent of movement of the slabs under tension or compression. The ends of the dowel bars 13 may be supported in the concrete slabs by

expansion caps or sleeves 13a, in accordance with usual practice, to permit of movement of one or both ends of the bars in the respective slabs.

These dowel bars 13 are supported in the aforesaid position by means of a supporting structure consisting of cooperating sections 14 and 15 having respectively horizontal extensions 16 and 17. The horizontal sections 16 and 17 are held together by means of a sleeve-like coupling 18 in such fashion as to permit relative movement between the sections 16 and 17, without destroying the connection which makes the supporting structure an integral unit.

In order that the supporting devices may be properly spaced and positioned across the roadway, tie bars 19 are provided, these bars being welded or otherwise secured to the respective sections of the supports. At the top of the sections 14 and 15, notches 20 and 21 respectively are formed in order that the dowel bar may be received and supported in the position illustrated. If desired, the notches may be formed by pressing out lugs 22 and 23, respectively, so that they will lie in a horizontal position. In order to align the bottom of the filler material interposed between the slabs 10 and 11, a lug 24 is pressed out of the bottom of the supporting structure.

In the form of the invention shown in Figs. 5, 6 and 7, the dowel bars are supported by the transverse tie bars 19 which are welded or otherwise secured to respective bars of wire supports 25 and 26. These bars are of L-shape and have horizontal portions 27 and 28 respectively, the ends of which are received within a sleeve-like coupling 29 having enlarged end portions 30 within which the wires 27 and 28 are received. Wire sections 31 are welded to the horizontal wires 28 to serve in the supporting capacity served by the lug 24.

In the form of the invention shown in Fig. 8, the support of Figs. 1 and 2 is formed in such fashion that the sections thereof are initially secured in position by means of shear pins 32. After the concrete has been poured and has set, relative movement between the sections 14 and 15 of the dowel bar support is permitted in response either to expansion or contraction of the concrete slabs, by shearing of the pins 32, thus permitting the same relative movement between the support sections as is accommodated by the clamps 18 and 29 in the forms of the invention shown in Figs. 2 and 7, respectively.

From the foregoing, it will be apparent that a dowel bar support has been provided by means of which relative movement between the adjacent ends of concrete slabs may be accommodated regardless of whether the movement occurs by reason of the forces in compression or tension. The device is simple of construction and relatively inexpensive, yet it serves effectively to position the dowel bars in a desired position and maintain them therein during the pouring and setting of the cement. After

the concrete slabs have set, relative movement therebetween is accommodated without the existence of restraining forces that have heretofore been exerted where the support structure has provided a positive tie between the ends of the slabs.

The present invention may, of course, be used in a varied type of service and is not restricted either to the type of material to be reinforced or to the particular service in which such material is to be used.

While the invention has been described with specific reference to the modifications shown in the accompanying drawing, it is not to be limited save as defined in the appended claims.

I claim:

1. A dowel bar support comprising a plurality of L-shaped elements each adapted to be disposed with one portion vertical and the other portion horizontal, the vertical portion of each element being provided with means to receive a dowel bar, and a coupling having two opposed portions spaced apart to receive therebetween the horizontal portions of two of said elements to connect the same for relative movement therebetween, the opposed portions extending lengthwise of the horizontal portions of the L-shaped elements a distance sufficient to prevent the weight of said dowel bar from buckling same.

2. A dowel bar support comprising a pair of L-shaped straps each adapted to be disposed with one portion vertical and the other portion horizontal, the vertical portion of each strap being provided with a recess to receive a dowel bar, and a coupling having two opposed sides adapted to receive therebetween and in overlapping relation the horizontal portions of said straps to connect said straps for relative movement therebetween.

3. A dowel bar support comprising a pair of L-shaped straps each adapted to be disposed with one portion vertical and the other portion horizontal, the vertical portion of each strap being provided with a recess to receive a dowel bar, and a sleeve coupling adapted to receive the horizontal portions for relative movement lengthwise thereof, said coupling being provided with wall portions adapted to engage the sides and side edges of the horizontal portions of said straps for a distance lengthwise thereof sufficient to hold the L-shaped straps from buckling under the load of the dowel bar.

4. A dowel bar support comprising pairs of L-shaped bars, each bar being adapted to be disposed with one portion vertical and the other portion horizontal, means to connect the vertical portions of two pairs of said bars to form a support on which to receive a dowel bar, and means including opposed wall portions to receive therebetween and in side by side relation the horizontal portions of each pair of bars to connect the bars for relative movement lengthwise thereof.

JOE G. CURRY.
